US0D1090674S

(12) **United States Design Patent** (10) Patent No.: **US D1,090,674 S**
(45) Date of Patent: ** Aug. 26, 2025

(54) **PHOTOGRAPHIC CAMERA**

(71) Applicant: **Orbbec Inc.**, Shenzhen (CN)

(72) Inventors: **Zuanze Lin**, Guangdong (CN); **Jianhua Tang**, Guangdong (CN); **Qin Liu**, Guangdong (CN); **Yao Wang**, Guangdong (CN); **Wei Li**, Guangdong (CN); **Bolin Wang**, Guangdong (CN)

(**) Term: **15 Years**

(21) Appl. No.: **35/521,665**

(22) Filed: **Jun. 21, 2024**

(80) **Hague Agreement Data**

Int. Filing Date: **Jun. 21, 2024**

Int. Reg. No.: **DM/238202**

Int. Reg. Date: **Jun. 21, 2024**

Int. Reg. Pub. Date: **Jul. 12, 2024**

(30) **Foreign Application Priority Data**

Apr. 18, 2024 (CN) 202430218977.5

(51) LOC (15) Cl. **16-01**

(52) U.S. Cl.

USPC **D16/218**; D16/202

(58) **Field of Classification Search**

USPC D16/200, 202-208, 218, 219; D14/125, D14/420

CPC G03B 17/02; G03B 19/04; G03B 17/56; G03B 17/04; G03B 15/03; H04N 23/50; H04N 23/51; H04N 23/54; H04N 23/55; H04N 23/62; H04N 23/63; H04N 7/181; H04N 7/183; H04N 7/18
